TAPPET CONSTRUCTION

Earl A. Thompson, Ferndale, Mich.

Application December 5, 1955, Serial No. 550,924

5 Claims. (Cl. 123—90)

This invention relates to a tappet and more particularly to a hydraulic tappet.

A hydraulic tappet, or a valve lifter, as it is sometimes called, is an element adapted to be located between an operator, such as a cam on a shaft driven by an internal combustion engine and a push rod for operating the poppet valves of the engine. This invention is primarily concerned with improvements in the construction of such tappets.

It is an object of this invention to provide a tappet of the hydraulic type that is designed so that a minimum of wear occurs between the moving parts thereof.

Another object of the invention is to provide a tappet of the above described type that is designed so that oil within the tappet may be utilized for lubricating the rocker arm assembly.

In the drawing:

Fig. 1 is a view partly in section showing a portion of an internal combustion engine with a tappet of this invention.

Fig. 2 is a longitudinal sectional view of the tappet illustrated in Fig. 1.

Fig. 3 is a sectional view taken along the lines 3—3 in Fig. 2.

Referring to the drawing, there is shown in Fig. 1 a portion of an engine including a cam shaft 10 having cams 12 thereon and an engine block 14 provided with an oil conduit 16 having branch passageways 18 communicating with bores 20. Within each bore 20, there is slidably arranged a tappet 22 of this invention. A rocker arm 24 for operating the valves of the engine, not shown, is actuated by tappet 22 through a push rod 26.

Referring now to Fig. 2, it will be observed that tappet 22 includes an outer body portion 28 generally in the form of a cylindrical member which is open at its upper end and has a base 30 closing its lower end. Base 30 is preferably made of cast iron and is united to the lower end of body 28 by welding as at 32. The manner in which the base 30 is welded to the lower end of body 28 is described in my application Serial No. 446,497, filed July 29, 1954.

Body 28 is preferably formed from a length of seamless steel tubing and is fashioned such as to provide a restriction 34 at the central portion thereof and a second restriction 36 at the open upper end of the body. These restrictions are in the nature of zones of reduced diameter. The inner face of base 30 is machined with a centrally located, generally conically-shaped socket 38 in which the lower end of a cylinder 40 is seated. Cylinder 40 has an outside diameter such as to provide clearance with the inner walls of body 28. Within cylinder 40, there is arranged a hollow piston 42, the bore 44 of which communicates with a passageway 46 in an extension 48 at the lower end of the piston. The open lower end of passageway 46 is controlled by a check valve in the form of a ball 50 biased to seat against and close the end of passageway 46 by means of a helical spring 52. The

2

space between the lower ends of piston 42 and cylinder 40 defines an oil chamber 53 into which the admission of oil is controlled by ball check 50. Piston 42 and cylinder 40 are detachably connected for relative operating movement by a spring ring 54. Ring 54 is seated in an annular groove 55 at the upper end of cylinder 40 and engages with a reduced portion 56 adjacent the upper end of piston 42. The reduced portion 56 is defined by a shoulder 58 at its upper end and a shoulder 60 at

10 its lower end. A cap 62 is telescoped over the upper end of piston 40 and is detachably connected therewith by means of a split ring 64 seated in an annular groove 66 adjacent the lower end of cap 62. The details of this split ring connection between the piston 42 and the cylinder 40 on the one hand and between the piston 42 and the cap 62 on the other hand is described in my application Serial No. 405,088, filed January 20, 1954.

Cap 62 is provided with a blind bore 68 which forms an extension of the bore 44 of piston 42. Adjacent its lower end, cap 62 is fashioned with a shoulder 70 which engages with the upper end of piston 42. Bore 68 communicates with the interior of body 28 by means of a radial passageway 72 extending through the side wall of cap 62. At its upper end, cap 62 is formed with a generally semi-spherical seat 74 for the reception of the lower end of push rod 26. At the lower end of seat 74, there is formed an axial passageway 76 which communicates with a radial passageway 78. Cap 62 slidably engages the side wall of body 28 at the restricted end 36 thereof. However, the tolerances between the outer diameter of cap 62 and the inner diameter of body 28 at the restriction 36 is such that there is a clearance between these members of between .0007" and .0015".

Push rod 26 comprises a hollow tube having generally semi-spherical ends, the lower end being provided with an opening 80 and the upper end with an opening 82. The upper end of push rod 26 engages with a semi-spherical shaped seat 84 at one end of rocker arm 24.

Referring now to Fig. 3, it will be seen that the upper end 36 of body 28 is flattened at one side thereof as indicated at 86. This flattened portion may be fashioned by simply striking the end of body 28 while it is retained in the die and has a suitable mandrel inserted therein of a desired shape. Cap 62 is formed of steel and has a flat face 88 machined at one side thereof so as to slidably engage with the inner face of the flat portion 86 at the end of body 28.

In operation, oil under pressure from the lubricating system of the engine flows through conduit 16 and branch passageway 18 into the space 90 that is provided between the side wall of bore 20 in the engine block and restriction 34 at the central portion of the tappet. This oil flows into the tappet body 28 through the opening 92 and fills the interior of the tappet body. The oil is free to flow through opening 72 into the bores 68 and 44 of the cap 62 and piston 42, respectively. Since this oil is under pressure, it flows through passageway 46, unseats ball 50 and fills oil chamber 53. As the cam 12 lifts the tappet, the oil in chamber 53 is subjected to compression, thus closing the ball check 50 and transmitting thrust from the member 40 to the piston 42. This thrust is transmitted through cap 62 and by the push rod 26 to the rocker arm 24. In view of the clearance between the outer surface of cap 62 and the inner surface of body 28 at the restricted zone 36 thereof, a portion of the pressurized oil in body 28 escapes through this clearance space and passes through passageways 76 and 78 through the opening 80 and upwardly into hollow push rod 26. The pressure of this oil as it escapes through this clearance space is reduced; but nevertheless, it is sufficient to rise in the hollow push rod 26 and flow outwardly therefrom at the spherical seat 84 of the

rocker arm 24. Thus, this oil is utilized for lubricating the connection between the push rod and the rocker arm. The rocker arm is provided with a passageway 94 extending from the spherical seat 84 to the bearing member 96 on which the rocker arm is pivoted. Therefore, the whole rocker arm assembly is oiled in this manner.

As is conventional, cam 12 is designed to engage base 30 of body 28 off center. This tends to rotate body 28. If cap 62 were permitted to rotate freely in body 28, a considerable amount of wear would occur between the contacting surfaces of piston 42 and cylinder 40 and to a lesser extent between cap 62 and body 28. However, by forming body 28 and cap 62 with the interengaged flat side wall portions 86 and 88, respectively, relative rotation of these members is prevented and the wear is maintained at a minimum. Even with this construction, however, it has been found that there is a slight amount of relative rotation between piston 42 and cylinder 40; probably because of vibration and the axial inclination of the load applied by push rod 26. This has been found desirable since it tends to equalize the very slight wear between piston 42 and cylinder 40.

I claim:

1. A hydraulic tappet comprising a generally cylindrical hollow body having an open end and a base at the closed end thereof adapted to be engaged by a cam to actuate said tappet, a cylinder in said body having a closed end and having an open end extending in the direction of the open end of the body, a piston slidably disposed in said cylinder and having one end projecting outwardly thereof, a cap on said projecting end of said piston slidably engaging the wall of said body adjacent the open end thereof, means on said body through which pressurized oil can be admitted into said body and from the interior of said body to said piston-cylinder assembly, said cap having at the outer end thereof means forming a seat for the reception of one end of a push rod and means for directing a small portion of the oil in said body to said seat in said cap, said last mentioned means comprising a passageway in said cap extending from said seat to the surface of the cap that is slidably engaged with said body adjacent the open end of the body, there being a slight clearance provided between said slidably engaged surfaces:

2. In an internal combustion engine of the type having poppet valves operated by a rocker arm assembly, the combination of means forming a bore in the engine, a hollow tappet body slidably arranged in said bore, said body having a piston-cylinder assembly therein, said assembly having an end portion projecting out one end of the body, said end portion having a seat therein, a tubular push rod extending from said seat to and engaged with said rocker arm assembly, whereby when said tappet is actuated, the valves are operated through said

55

push rod and rocker arm assembly, means for admitting pressurized oil to said bore, said body having an aperture therein communicating with said bore to admit pressurized oil to the interior thereof, means for bypassing a small portion of the oil within said body to said seat, said push rod being open at its opposite ends, whereby said oil conducted to said seat is permitted to rise through said push rod to lubricate said rocker arm assembly.

10 3. The combination called for in claim 2 wherein said end portion of said piston-cylinder assembly slidably engages a side wall portion of said body, said end portion having a passageway therein extending from said seat to the surface of said end portion slidably engaging the side wall portion of the body, there being a slight clearance provided between said slidably engaged surfaces, whereby oil in said body is permitted to flow through said clearance space and passageway to said push rod.

15 4. The combination called for in claim 3 wherein said rocker arm assembly includes a passageway communicating with the open end of the push rod with which it is associated.

5. A hydraulic tappet comprising a generally cylindrical hollow body having an open end and a base at the closed end thereof adapted to be engaged by a cam to actuate said tappet, a cylinder in said body having a closed end and having an open end extending in the direction of the open end of the body, a piston slidably disposed in said cylinder and having one end projecting outwardly thereof, a cap on said projecting end of said piston slidably and non-rotatably engaging the wall of said body adjacent the open end thereof, means on said body through which pressurized oil can be admitted into said body and from the interior of said body to said piston-cylinder assembly, said cap having at the outer end thereof means forming a seat for the reception of one end of a push rod and means for directing a small portion of the oil in said body to said seat in said cap, said last mentioned means comprising a passageway in said cap extending from said seat to the surface of the cap that is slidably engaged with said body adjacent the open end of the body, there being a slight clearance provided between said slidably engaged surfaces.
